UNITED STATES PATENT OFFICE.

SHIRO ISHIMATSU, OF LOS ANGELES, CALIFORNIA.

AUTOMOBILE HEATER.

1,427,475.

Specification of Letters Patent. Patented Aug. 29, 1922.

Application filed April 26, 1921. Serial No. 464,622.

To all whom it may concern:

Be it known that I, SHIRO ISHIMATSU, a subject of the Emperor of Japan, residing in the city and county of Los Angeles and State 5 of California, have invented a new and useful Automobile Heater, of which the following is a specification.

This invention relates to a heating device for automobiles, and comprehends an organization of tubular conduits adapted to contain circulated air, previously heated from proximity to the exhaust gases of the explosive motor, and capable of radiating heat within the automobile.

15 The objects of the invention are to provide a compact and efficient device for abstracting heat from the exhaust gases from the motor, and for distributing the abstracted heat within the automobile.

20 The invention resides in the construction and arrangement of the elements composing the heat distributing device.

Upon the annexed drawings, Figure 1 is a diagrammatic view of the air heating and 25 air circulating elements embodying my invention. Fig. 2 is an end view of the heating chamber and conduits. Fig. 3 is a side view of the automobile heater applied to and supported in a motor vehicle.

30 Referring to the drawings, the apparatus comprises an outer casing 11, and an inner casing 12 concentric with the outer casing, and forming, respectively, the annular chamber 13 and cylindrical chamber 14. The exhaust tube 15, extending from the muffler 16, passes concentrically through the inner chamber 14. The outer chamber 13, therefore, forms a non-conducting space for retaining the heat within the inner chamber.

35 40 A pipe conduit 17, has a spiral section 18, winding around the exhaust tube 15, and within the chamber 14. This conduit 17 extends upwardly to the radiating sections 19, where the heat is emanated within the automobile. From the radiating sections, the air, somewhat cooled, circulates back to the

annular chamber 13, and enters at one end thereof. Thence the air circulates to the opposite end and enters the inner chamber 14, through the opening 20. Thence the air traverses the inner chamber and enters the tubular coil 18, through the open end 21, and again abstracts a portion of the heat from the exhaust gases.

45 In use, the expansion of the heated air within the coil will cause the same to flow upwardly through the radiating coils or sections. It may be noted that the gases of combustion do not pass through the circulating portions of the device. The air, which 50 returns from the radiating sections by gravity, is thus brought adjacent to new gases of combustion, and thereby reheated.

55 It is to be understood that minor changes in the construction may be resorted to without departing from the spirit of the invention.

What is claimed is:

60 In an automobile heating system, the combination with the motor exhaust tube and muffler, of a cylindrical casing disposed on the exhaust tube and concentric therewith and having its forward end adjacent to the muffler, a cylindrical wall within the casing and forming outermost and innermost annular intercommunicating chambers concentric with the motor exhaust tube, radiator pipes located at a higher level than the cylindrical casing, a coil of pipe encircling the motor exhaust tube and within the innermost annular 65 chamber, said coil having one end extending from the casing adjacent to the muffler and the opposite free end in open communication with the inner chamber, a conduit connecting the coil of pipe with the radiator pipes, and a conduit connecting the radiator pipes and the outermost annular chamber, the said coil of pipe, intercommunicating chambers, conduits and radiator pipes being arranged for a continuous circulating air passage.

SHIRO ISHIMATSU.
